Primary Examiner — Cynthia Underwood(74) *Attorney, Agent, or Firm* — Dale J. Ream**CLAIM**

The ornamental design for a laptop keyboard and mouse tracking pad protection sleeve, as shown and described.

DESCRIPTION

FIG. 1 is a front elevation of a laptop keyboard and mouse tracking pad protection sleeve showing my new design in use;

FIG. 2 is a front elevation of a laptop keyboard and mouse tracking pad protection sleeve;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

In the drawings, the broken lines represent unclaimed environment subject matter and form no part of the claimed design.
